US0D1021304S

(12) **United States Design Patent** (10) Patent No.: **US D1,021,304 S**
(45) Date of Patent: ** Apr. 2, 2024

(54) **VACUUM CLEANER**

(71) Applicant: **Anker Innovations Technology Co. Ltd.**, Changsha (CN)

(72) Inventors: **Shihua Tang**, Shenzhen (CN); **Zongshuai Xu**, Shenzhen (CN)

(73) Assignee: **Anker Innovations Technology Co. Ltd.**, Changsha (CN)

(**) Term: **15 Years**

(21) Appl. No.: **29/823,131**

(22) Filed: **Jan. 14, 2022**

(51) LOC (14) Cl. **15-05**

(52) U.S. Cl.

USPC **D32/18**

(58) **Field of Classification Search**

USPC ..... D15/199; D21/526, 578; D32/15, 16, D32/17, 18, 21, 23, 25, 31, 32, 38, 39 CPC ... A47L 7/12; A47L 7/22; A47L 7/225; A47L 7/24; A47L 7/28; A47L 7/32; A47L 7/362; A47L 7/365; A47L 9/02; A47L 11/22; A47L 11/24; A47L 11/32; A47L 11/33

(74) Attorney, Agent, or Firm — Banner & Witcoff, Ltd.

(57) **CLAIM**

The ornamental design for a vacuum cleaner, as shown and described.

DESCRIPTION

FIG. 1 is a front perspective view of a vacuum cleaner showing our new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a rear perspective view of an alternative embodiment of the vacuum cleaner of FIGS. 1-8; and,

FIG. 10 is a rear perspective view of another alternative embodiment of the vacuum cleaner of FIGS. 1-8.

The broken lines depicting the remainder of the vacuum cleaner form no part of the claimed design.

1 Claim, 10 Drawing Sheets
